AUTOMATIC ELEVATOR

Thomas Charles Gower, Greenville, S. C.

Application August 12, 1947, Serial No. 768,230

6 Claims. (Cl. 187—29)

1

This invention relates to automatic elevators, and more especially to means for controlling operation of such elevators. The present invention represents a further development and improvement of the inventions disclosed in my copending applications Serial No. 594,623, filed May 19, 1945, now Patent Number 2,425,312 of August 12, 1947 and Serial No. 650,252, filed February 26, 1946.

In my above identified copending applications, I have disclosed means for automatically controlling the operation and direction of rotation of a single phase electric motor of the type having a starting winding and associated means for automatically disconnecting the starting winding after the motor has started. More specifically, a capacitor motor is used according to my copending applications, and in one instance a control system particularly adapted for operating a door closure is disclosed, and in the other instance the application is directed to automatic operation of an elevator or hoist between a maximum of three floor levels.

According to the present invention, a control system is disclosed for automatically operating an elevator or the like between more than three floor levels. This control system, as in my prior copending application, is particularly adapted for use with a capacitor motor. The motor is arranged to effect movement of an elevator car disposed for travel between floor levels, and the control system provides means for controlling the operation and direction of movement of the elevator.

The control system of the present invention is described further below in connection with the accompanying drawing, in which:

Fig. 1 is a circuit diagram illustrating an embodiment of the control system of this invention for five floor levels, and in which the elevator car is assumed to be at rest at the first floor level; and,

Figs. 2, 3, 4 and 5 are corresponding fragmentary details to illustrate the operation of the selector mechanism included in the control system as the elevator car is moved to the second, third, fourth, and fifth floor levels, respectively.

The capacitor motor for effecting movement of the elevator car is represented generally in Fig. 1 by the numeral 10. The motor 10 may be arranged to effect movement of the elevator car (not shown) in any conventional manner such as is illustrated, for example in my copending application Serial No. 650,252.

The running winding for the motor 10 is shown

2

at 11 and the starting winding at 12. The starting winding circuit includes a centrifugal switch 13 for automatically disconnecting the starting winding 12 after the motor has started, and a reversing switch 14. A line circuit is provided at 15 for operation of the motor 10, and the motor 10 is mechanically associated (as indicated by the dotted line at 16 in Fig. 1) with an auxiliary centrifugal switch 17, a frictionally operated contact making device 18, and a selector mechanism S. The purpose and function of these mechanically associated elements is described further below.

The line circuit 15 includes a normally open switch 19 which is controlled by a main line relay M. The relay M is energized from a control circuit 20 connected through a transformer 21 across the line circuit 15, although it will be recognized that the transformer 21 will not be required if relays equipped with individual transformers are used. The control circuit 20 runs to a plurality of control stations from which it may be closed to energize the main line relay M as will appear presently. The previously mentioned auxiliary centrifugal switch 17 is arranged for making a holding circuit 22 from the control circuit 20 to relay M during operation of motor 10.

The control stations for closing the control circuit 20 comprise a plurality of manually operable switch members, in the nature of a push button or the like, arranged on the elevator car and corresponding in number to the number of floor levels, as indicated at C1, C2, C3, C4, and C5; and a similar manually operable switch member at 35 each of the floor levels as at F1, F2, F3, F4, and F5. The control circuit 20 runs in parallel to these switch members so that it may be closed at any one of them to energize the main relay M and start motor 10.

40 The control circuit 20 is also connected through the above mentioned manually operable switch members to energize a second relay R which is arranged to control the reversing switch 14, and consequently the direction of rotation of motor 10. The previously noted frictionally operated contact making device 18 and selector mechanism S are interposed in the connection of the control circuit through relay R for automatically orienting this relay according to the desired direction 45 for movement of the elevator.

50 This arrangement will be understood by noting that a connection 23 runs from the switch members C1 and F1 at the first floor level directly through relay R to control circuit 20, which means that relay R will always be energized when

called to the first floor level from either of these control stations, and that the position of reversing switch 14 corresponding to energized condition of relay R will also correspond to operation of motor 10 in a direction for downward movement of the elevator car. Consequently, for upward movement of the elevator car, relay R will always have to be de-energized to obtain operation of motor 10 in the opposite direction. For this purpose, the control circuit 20 also runs to relay R through a holding circuit 24 which includes normally closed contacts as shown at 25. These contacts are controlled by a relay 26 which is energized through connections 27 and 28 from the control stations above the first floor level, when the elevator car is at the first floor as shown in Fig. 1, so that the contacts 26 are automatically opened to orient the reversing switch 14 properly whenever the elevator car is called from the first floor level to an upper floor level.

The connections from the control stations for intermediate floor levels run to the relay 26 through the selector mechanism S at contacts a, b, and c, respectively. The selector mechanism S has contacting shoes m and n for making the contacts a, b, and c, and as noted above it is mechanically associated with motor 10. As shown in Fig. 1, upward movement of the elevator car is assumed to correspond to operation of motor 10 in the direction of clockwise rotation with corresponding rotation of the selector mechanism S, so that upon movement of the elevator car to the upper floor levels the shoes m and n will progressively assume positions with respect to contacts a, b, and c as illustrated in Figs. 2, 3, 4, and 5. And as shoe m is tied to connection 23, and shoe n to connection 27, the reversing switch 14 will still be oriented properly no matter where the elevator car is or in which direction it is called.

The foregoing arrangement provides means for starting the motor 10 to effect movement of the elevator car in the proper direction for travel to a selected floor level. To stop the elevator car after the selected floor level has been reached, provision is made for reversing the starting winding 12 and reconnecting it to buck the running winding 11 and thus stop motor 10. For this purpose, a bridging circuit 29 is arranged across the centrifugal switch 13 to run in parallel to contacts at each of the floor levels as indicated at X1, X2, X3, X4, and X5. These contacts are disposed to be made by means associated with the elevator car, such as a shoe 30 as described further in my above mentioned copending application Serial No. 650,252.

The bridging circuit 29 to contacts X1 and X5 at the first and top floor levels are otherwise closed so that when the elevator car reaches either of these floor levels the shoe 30 completes the bridging circuit to reconnect the starting winding 12 and stop motor 10. To provide for proper orientation of reversing switch 14 when the starting winding 12 is reconnected, the frictionally operated contact making device 18 is interposed in the holding circuit 24 for the relay R. It has previously been pointed out above that for upward movement of the elevator car, relay R should be de-energized and that it must be energized for downward movement, and it will be apparent that the opposite conditions must prevail to reconnect starting winding 12 for stopping motor 10 following upward or downward movement of the elevator car. Also, it has been assumed above that upward movement of the elevator car corresponds to operation of motor 10 in

75 to said motor, said line circuit including a nor-

the direction of clockwise rotation, so that movement of the frictionally operated contact making device 18 will be in a corresponding direction.

The frictionally operated contact making device 18 is preferably of the type described in detail in my prior copending applications, and comprises essentially a friction collar mounted for rotation on a shaft except when opposed and a contact making member extending from this collar as illustrated generally at 31 in Fig. 1. With upward movement of the elevator car and consequent clockwise rotation of motor 10, the contact making device 18 will shift until member 31 makes the contacts at 32 in holding circuit 24, and as relay 26 has no holding circuit, the holding circuit 24 will be automatically closed at contacts 32 after the motor has started upon call to an upper floor to energize relay R for orienting reversing switch 14 properly to stop motor 10 when the call floor is reached. If the call floor is the top floor, then the elevator car will travel until shoe 30 makes the contacts at X5 without further adjustment of the control system. And if the elevator car were at the top floor and were called to the first, the contact making device 18 would shift in a counterclockwise direction after motor 10 started to a position determined by a stop 33 so that contacts 32 would open to de-energize relay R and allow proper reconnection of starting winding 12 for stopping when contacts X1 were reached.

If the call floor is an intermediate floor, additional connections are made selectively through relays B2, B3, and B4 to complete the bridging circuit 29 to contacts X2, X3, or X4 as desired. The relays B2, B3, and B4 are connected in control circuit 20 through the control stations at the respective intermediate floor levels, so that they are energized whenever the control circuit 20 is closed for the corresponding intermediate floor level. Also, the relays B2, B3 and B4 are provided with a holding circuit 34 running from the circuit for motor 10 so that when energized to effect stopping at one of the intermediate floors they are automatically de-energized when the motor 10 stops.

A further feature of the control system of the present invention is an auxiliary relay 35 arranged to prevent control of movement of the elevator car from any of the control stations after the motor 10 has been started from another control station. The relay 35 is arranged to control normally closed contacts 36 in the control circuit 20. This relay 35 is connected through a transformer 37 across the centrifugal switch 13, so that until the centrifugal switch 13 is disconnected upon starting of motor 10, relay 35 will not draw current. When the centrifugal switch 13 opens, however, relay 35 will be connected in series with the running winding so that it will be energized to open contacts 36 and in turn open control circuit 20 to render all of the control stations inactive until motor 10 is stopped.

I claim:

65 1. In an automatic elevator, the combination with an elevator car disposed for travel between at least four floor levels, of means for moving and controlling said elevator car for travel between said floor levels comprising a single phase 70 electric motor arranged to effect movement of said elevator car, said electric motor having a starting winding and associated means for automatically disconnecting the starting winding after the motor has started, a line circuit running

normally open switch, a relay arranged to close said switch when energized, a reversing switch in the circuit of said starting winding, a second relay arranged for controlling said reversing switch, a plurality of bridging circuits across said centrifugal switch running in parallel to contacts at each of said floor levels, said contacts being made by means associated with said elevator car when said car is moved to the respective floor levels, the bridging circuits for intermediate floors being normally open, and additional relays being arranged for selective closing of said bridging circuits for the intermediate floors, a plurality of manually operable switch members on said elevator car corresponding in number to the number of floor levels, a manually operable switch member at each floor level, a control circuit connected across said line circuit ahead of said line switch for energizing said relays, all of said manually operable switch members being connected in parallel for closing said control circuit to said first and second relays and for selective closing of said additional relays, and means interposed in the control circuit to said second relay for automatically orienting said relay according to the desired direction for movement of said elevator car.

2. In an automatic elevator, the combination defined in claim 1 and further characterized in that the single phase electric motor is a capacitor motor.

3. In an automatic elevator, the combination defined in claim 1 and further characterized in that an auxiliary centrifugal switch is mechanically associated with said motor for making a holding circuit from said control circuit to said first relay during operation of said motor.

4. In an automatic elevator, the combination defined in claim 1 and further characterized in

that an auxiliary relay is connected through a transformer across the centrifugal switch in the winding of said motor, said auxiliary relay being arranged to open normally closed contacts in the control circuit running to said manually operable switch members and thereby prevent control of said elevator car from said switch members during operation of said motor.

5. In an automatic elevator, the combination defined in claim 1 and further characterized in that said last mentioned means for orienting said second relay includes a selector mechanism mechanically associated with said motor for rotation in accordance with the direction of movement of said elevator car, said selector mechanism having contacting shoes arranged for making contacts selectively in the control circuits from the manually operable switch members for the intermediate floor levels to said second relay in accordance with the position of said elevator car with respect to said intermediate floor levels.

6. In an automatic elevator, the combination defined in claim 1 and further characterized in that said last mentioned means for orienting said second relay includes a holding circuit from said control circuit to said second relay, and said holding circuit includes means mechanically associated with said motor for automatically closing said holding circuit when said motor is operating in one direction and a relay arranged to open normally closed contacts in said holding circuit, said relay being connected for energizing by the control circuits from the manually operable switch members at floor levels requiring operation of said motor in the opposite direction.
